BUILDER MECHANISM

Fred M. Roddy, Providence, R. I., assignor to
H & B American Machine Company, a corpora-
tion of Maine

Application February 13, 1941, Serial No. 378,745

5 Claims. (Cl. 242—43.4)

This invention relates to builder mechanisms, and more particularly to a builder mechanism for use in textile twisting machinery such as, for example, a large package twisting machine for rayon; and has for one of its objects the traversing of the packaging means from end to end of the yarn receiver at constant speed during the winding operation.

Another object of the invention is to provide a builder mechanism which will raise and lower the ring rail at a constant speed throughout its entire vertical traverse from the top to the bottom ends thereof with no dwell at the terminal extremities of its stroke upon reversal of the direction of traverse of the rail.

Another object of the invention is to provide a builder mechanism for actuating the traversing member of the packaging means in which the stroke or length of traverse of the traversing member will be controlled and varied according to a predetermined cycle of operation.

Another object of the invention is the provision of a builder motion for building a headless bobbin having a lower main cylindrical section with substantially straight sides down to the bobbin base and an upper top section of sloping formation the contour of which will prevent sloughing-off of the top end convolutions and yet will permit the wound textile material to be pulled off easily from the upper end of the bobbin.

Another object of the invention is to provide a builder mechanism which will actuate the traversing member of the packaging means and will be of a sturdy construction and will run for considerable periods of time without attention.

Another object of the invention is to provide a builder mechanism of extreme flexibility capable of actuating the traversing member of the packaging means at high speed through a series of cycles during the building of the bobbin and yet will permit the ready removal and the replacement of the cams controlling the building of bobbins of desired contour.

Another object of the invention is to provide a builder mechanism which will permit random doffing of the bobbins.

Another object of the invention is to provide a builder mechanism which is of a unit construction the parts of which can be readily assembled at a work bench, and also having a compact standardized arrangement which will be universal and can be placed in any of the usual locations of such mechanisms in textile machines and thus will eliminate the use of special designs to fit specific types of machines as heretofore required with the prior arrangements.

Another object of the invention is to provide a builder mechanism incorporating a cam shaped to impart constant-speed reciprocation to the traversing member associated with the packag-

ing means in order that the slope of the cam face will be gentle and reversals of direction easy so that rapid acceleration and difficult reversal of the traversing member will therefore be avoided.

Another object of the invention is to provide a builder mechanism incorporating a main cam of a generally heart-shaped formation, the contour of which is a uniformly-advancing spiral for each half of the cam and whose manufacture can be generated mechanically on a machine tool, thereby obviating any laying out or designing of the cam contour on a drafting board as is the usual practice with cam shapes of irregular contours.

Another object of the invention is the driving by means of simple gearing of the mechanism which shortens the stroke and thus avoids the use of previous mechanisms using ratchets and pawls or pick motions for actuating the mechanism serving to change the stroke of traverse.

Another object of the invention is the provision in association with the main cam mechanism of the builder motion of an auxiliary cam for progressively building the sloping top of a bobbin, and the use of a planetary gear arrangement cooperating with part of the cam mechanism of the main builder mechanism so as to vary the length of the stroke or traverse.

With these and other objects in view, the invention consists of certain novel features of construction, as will be more fully described, and particularly pointed out in the appended claims.

Referring now to the drawings wherein like reference characters denote like parts throughout the several views of the accompanying drawings, in which—

Fig. 1 is a side elevation of a portion of a traveler type ring spinning or twisting frame embodying my improvements;

Fig. 2 is a front elevational view of the builder unit, housing my improved builder mechanism and showing the main traverse cam and the "creep" or auxiliary traverse-control cam in their extreme positions of rotary movement;

Fig. 3 is a detail sectional view taken on line 3—3 of Fig. 2, showing the arrangement of the main cam, the slides, and the gearing for driving the main cam;

Fig. 4 is a detail sectional view taken on line 4—4 of Fig. 2 showing the arrangement of the "creep" cam, the rocker arm, and the planetary gearing for driving the "creep" cam;

Fig. 5 is a fragmentary detail end elevation view, with the "creep" cam removed, showing the rocker arm, in dot and dash outline, in its two extreme positions of oscillatory movement, and the planetary gearing, in full lines, for driving the "creep" cam;

Fig. 6 is an enlarged detail sectional view of part of the builder mechanism shown in Fig. 4,

but with some of the parts illustrated in full outline;

Fig. 7 is an enlarged detail transverse sectional view of the upper slide and its mounting, taken on line 7—7 of Fig. 2;

Fig. 8 is an elevational view of a headless type of bobbin carrying a yarn package provided with a build for which the builder mechanism of the present invention is adapted;

Fig. 9 is an elevational view of one type of bobbin having a yarn package provided with a build for which the mechanism shown in the drawings is adapted; and

Fig. 10 is a graphical representation of the manner in which the stroke of the traverse rail carrying the packaging means is progressively lengthened and shortened while being traversed up and down at uniform speed as the yarn or thread is being laid on the spool when the builder mechanism illustrated in the drawings is used.

Heretofore, in the building of bobbins having cylindrical yarn packages provided with a tapered build at the top, the superposed layers of yarn or thread have been laid on the bobbin by suitable packaging means traversed by a traversing member actuated by a builder mechanism designed for a long stroke of traverse during cross-winding of the textile material upon the bobbin; and the tapered build at the top or nose of the final package is accomplished by the combination of an accelerated traverse speed and also by a shortened traverse stroke effected by means of either a ratchet and a pawl mechanism or by a pick mechanism which actuates an eccentric or a screw to effect an intermittent winding-up of the lift chain and to elevate, by small increments, the top end level or limit of the stroke of the rail and thus shorten its traverse while keeping the bottom limit of the stroke of traverse unchanged. Such prior mechanisms have several disadvantages, the principal objections being that they lack flexibility, are not adapted to high speed operation, have lost motion, and sometimes require winding back to their starting position after doffing of the wound bobbin and hence do not permit "random" doffing. Furthermore, the pawls and the ratchets are found to be subject to considerable wear so that not only is the life of the mechanism relatively short, but in many instances it requires frequent attention during its operation. Also, such previous mechanisms do not permit as complete flexible control over the shape of build of the yarn or thread at the top of the bobbin, since screws and eccentrics are used to vary the stroke and length of traverse of the traversing member carrying the packaging means. Thus, an aim of the present invention is the provision of a simplified and improved builder mechanism for textile packaging apparatus wherein exact control of the length of stroke of the traversing member and the shape of build on a bobbin is obtained so as to generate any desired shape of build at the top of the bobbin. In accordance with the present invention such a build on a bobbin can be produced by means of simple gearing and thereby eliminate the ratchets and pawls and pick mechanisms used in the usual builder motions. To this end the present invention contemplates a novel builder mechanism which embodies two cams arranged to operate concurrently according to a predetermined cycle of operation, but at different speeds of rotation, one of the cams being a main cam

which co-acts with a cam follower member carried by a slide to impart uniform reciprocatory motion thereto at all times during rotation of the main cam. To convert this reciprocatory motion of the slide into oscillatory motion, at constant speed, of a builder lever operatively connected to a traversing member carrying the packaging means, I provide a rocker arm which is actuated by and oscillated in response to the reciprocatory movements of said slide, and this rocker arm drives a second slide which has parallel motion with the first slide and is operatively connected to an arm on a rocker shaft to oscillate the lever for actuating the traversing mechanism to bring about the desired traversing movements of the traversing member carrying the packaging means such as, for example, the reciprocation of the lifting mechanism for raising and lowering the reciprocating ring rail of a twisting machine for textiles. Since the aforementioned two slides have parallel motion with respect to each other the linkage between the rocker arm and the arm on the shaft carrying the lever for reciprocating the traversing mechanism is constant which result would not be true of links pinned together due to the change of centers. Associated with the rocker arm and rockable therewith is an auxiliary cam which I term as the "creep" cam, and this cam, although simultaneously going through the same oscillatory movement as the rocker arm with which it is associated, has slight progressive rotational movement relative to the rocker arm and will make one complete revolution with respect to the rocker arm for a predetermined cycle of complete oscillations thereof to reciprocate a block on which is rotatably mounted the roller for driving the second slide. Thus, the "creep" cam in making one complete revolution on the rocker arm will cause the block to progressively move radially inwardly and outwardly with respect to the pivotal axis of the arm to progressively vary the radial distance of the lever arm of the rocker arm that drives the lower slide from a predetermined minimum up to the length of the lever arm so that during the continuous motion of the main cam, there will be repeated cycles of long and short strokes of the lower slide.

Referring to the drawings, I have shown a portion of a traveler type ring twisting frame for spinning or twisting artificial silk, such as rayon, and which has extending longitudinally between the end frame members 15 the fixed horizontal spindle supporting rails 16, one being disposed at each side of the machine frame, upon which a plurality of vertical twisting spindles generally designated 17 are mounted in the usual manner for rotation thereon for carrying and rotating the yarn receivers or bobbins 18 on which the yarn is to be wound and which may be of either of the types shown in Figs. 8 and 9 respectively. As the yarn 20 is wound upon the receivers or bobbins 18 as it is supplied from a suitable source of supply (not shown), it is directed and guided through the yarn guides 21 which are mounted on the vertically traversable guide rail 22 and thence passes to the bobbins through the travelers 24 carried on the rings 25 which are secured in ring holders 26 mounted on a vertically traversable ring rail 27. The ring holders 26 preferably are of the type described and claimed in my prior Patent No. 2,033,741, granted March 10, 1936, although other known forms of ring holders may be used, if desired. The spindles 17 may be any of the usual individual knee-brake type, and

they are provided with the customary whorls 28 for rotating the spindles and the bobbins in unison, and driven by the usual driving bands (not shown) which are rotated from a suitable source of power, such as for example a plurality of pulleys on a power shaft (not shown) that extends longitudinally of the machine, as is a known arrangement in spinning or winding machines.

In order to traverse the ring rail and the guide rail during the winding operation, each ring rail 27 and each guide rail 22 is separately mounted upon a plurality of lifter rods 30 and 31 respectively, one of each of said lifter rods being shown in the drawings, and the upper ends of the rods 30 and 31 are connected fixedly in a suitable manner to their respective rails. Mounted on the lower ends of the rods 30 and 31 are the shoes 32 and 33 respectively which have a flat bottom face engaged by the respective rollers 34 and 35 rotatably mounted on a lifting lever 36. The lifting lever 36 is fast on one end of a cross shaft 37 which is journaled in the brackets 38 suitably attached to the inner side of the rails 16 and extends transversely of the machine frame to be rocked by a lever 39 which is fast on the other end of the cross shaft 37 and oscillated by a connecting rod 40 having pivotal connection at its opposite ends with the lever 39 and a builder lever 41 fast on the end of an oscillatable shaft 42 which projects exteriorly of the housing 44 of the builder unit generally designated 45, the shaft 42 being positively oscillated by the mechanism of the builder motion therein which is to be presently described in greater detail.

The builder mechanism of the builder unit 45 comprises as the principal elements thereof, a main cam 48 of heart-shaped contour which is continuously rotated at uniform speed to effect the reciprocation of a slide 49 at a uniform rate of speed, a rocker arm 50 oscillated by the slide 49 in response to its reciprocatory movements, a reciprocable transfer bar 51 connecting the rocker arm 50 to a rocker lever 52 and reciprocated in response to the oscillatory movements of the rocker arm to transmit the oscillations of the same to the rocker lever 52 to effect corresponding oscillatory motion of the shaft 42 and the builder lever 41 thereon, and an auxiliary mechanism to control the oscillatory motion of the shaft 42 by varying the extreme limit of the stroke of the reciprocable transfer bar 51 in one direction comprising an auxiliary cam 54 oscillatable with the rocker arm 50 and also independently rotatable relative thereto during a definite predetermined cycle of oscillations of the rocker arm for progressively varying the leverage ratio of the connection between the rocker arm 50 and the reciprocable transfer bar 51.

As illustrated in Figs. 2 and 3, the heart cam 48 is affixed to the end of the hub 55 of the drive gear 56 in a suitable manner, as by means of the threaded studs 57 which pass through suitable openings in the cam side and have their inner ends screwed into tight engagement with the tapped holes 58 provided in the end face of the hub 55. The main cam 48 is rotated continuously at constant speed by the drive gear 56 which is driven, preferably at a relatively slow speed, by the pinion 60 fast to one end of the power shaft 61. Suitable means may be provided for driving the power shaft 61 at a slow speed from the head of the machine, such as for example a speed-reducer unit generally designated by the numeral 63 the mechanism of which may comprise a worm wheel (not shown) secured

on the other end of the shaft 61 and driven by a worm (not shown) fast on the longitudinally-extending shaft 65 which is positively driven in a manner well understood in the art from the head of the machine. As illustrated in Fig. 3, the gear 56 is provided with a suitable bearing sleeve 66 pressed into the hub 55 of the gear 56 for rotating of the gear about the fixed pin 67 which has a portion 68 non-rotatably secured in the hub 10 70 of the housing 44 in a suitable manner such as, for example, by means of a key or a set screw (not shown).

Referring to Figs. 2, 3, and 4, the main cam 48 is shown with its peripheral face in an operative engagement with the periphery of the cam follower roller 71 rotatable on the pin 72 carried by the end portion of the depending arm 73 of the bracket 74 which is offset from and secured to the outer side face of the upper slide 49 near one 15 end thereof in a suitable manner, as by machine screws 75. As shown in Figs. 2, 3, and 7, the upper slide 49 consists of a long, narrow, U-shaped plate provided with two spaced slotted openings 76 through which extend the shanks of the T-shaped blocks 77 the heads of which are accommodated within the channel portion of the slide and hold the slide in the channel-way 78 of the horizontally disposed U-shaped guide member 79 for free sliding movement therein. Screws 80 secure the 20 blocks 77 to the back wall of the channel member 79 which in turn is suitably fixed to the housing 44 of the builder unit.

In order that the reciprocatory motion of the slide 49 may be transferred to the rocker arm 50 to impart oscillatory motion thereto, I provide a hardened roller 81 which is freely rotatable on the pin 82 between and at the outer ends of the arms 83 of the rocker arm 50, and this roller engages and rolls back and forth along the 25 surface of the hardened face plate 84 secured on one end of the bracket 74, whereby the normal uniform rotary movement of the cam 48 effects reciprocation of the slide 49 and thus, through the rolling connection of the roller 81 with the bracket 74, serves to oscillate the rocker arm 50 back and forth in response to the movement of the slide.

In order that this oscillatory motion of the rocker arm 50 may be transmitted by the transfer bar 51 to the rocker lever 52, I form the other end of the rocker arm 50 of a bifurcated construction (see Fig. 4) having the spaced arms 83', and the outer end of these arms is provided with a rectangular slot 85 within which is mounted the slide block 86 which bridges the arms and has mounted therein a cam follower roller 87 freely rotatable on a pin 88. The roller 87 engages and rolls back and forth along the outer surface of a hardened face plate 89 affixed to the adjacent end of the transfer bar 51, thereby imparting reciprocating movement thereto in response to the oscillatory movements of the rocker arm as the roller 87 rolls up and down on face plate 89 during oscillatory movement of the rocker arm 50. The transfer bar 51 is held offset from the U-shaped slide 90 by the spaced studs 91 provided on the back of the bar and the bar is fixedly secured to the slide in any known manner in the art, such as by screws 93. The lower slide 90 is of similar construction to the upper slide 49 and is held in the channel-way 95 of the U-shaped guide member 96 by T-shaped blocks (not shown) whereby the slide 90 has free sliding movement in the lower guide

member 96, which in turn is fixed to the housing 44.

A cam roller 100 pinned to the arm 52 by a pin 101 and freely rotatable thereon contacts the hardened sleeve 102 attached to the transfer bar 51. Thus, the longitudinal reciprocating motion of the transfer bar 51 will therefore be converted into oscillatory motion of the rocker lever 52 which is keyed to and oscillates the shaft 42 and through it imparts oscillating motion to the builder lever 41. Such movement of the builder lever reciprocates the connecting rod 40, oscillates the shaft 37 and the lever 36 and effects vertical reciprocatory motion of the lifter rods 30 and 31 to raise and lower the ring rail 27, and the thread guide rail 22 respectively, during winding of the yarn on the bobbins 18.

It will be seen from the description of the builder motion thus far described that the main cam 48 in normal operation rotates continuously at uniform speed and there will be produced a vertical traversing of the ring rails and guide rails at constant speed throughout their traverse with no dwell at the ends of the stroke when the direction of traverse is reversed.

A further feature of this invention resides in the construction and arrangement of the builder motion for changing the length of traverse of the ring rail in order to produce the long, sloping top T₁ or T₂ on either of the bobbins 18 as shown in Figs. 8 and 9 respectively, this build being formed by the traversing action of the ring rail of the spinning or twisting machine just described; and to this end I provide means for progressively varying the vertical traverse or stroke of the ring rail during a predetermined cycle of its operation. In the illustrated embodiment of the invention, I show an auxiliary cam 105 which I have termed the "creep" cam since it is constructed and arranged to have progressive rotational movement relative to the rocker arm 50 and to vary its angular position with respect to the arm 50 by a slight amount for each cycle of swinging movement with the rocker arm 50, and I utilize this "creeping" action or progressive rotational motion of the cam 105 to progressively move the slide block 86 from one end of the slot 85 to the other end thereof. Thus, I provide in the inner face of the cam 105 a groove 103 which receives a cam follower roller 104 loosely rotatable upon the pin 104' fixed to the slide block 86. The groove 103 is made of such shape or contour as to vary the fulcrum length between the reciprocable pin 104', as it moves with the block 86, and the axis about which the cam 105 rotates, in accordance with whatever rule or law according to which the cam 105 must necessarily move to produce the desired shape of bobbin top. It will thus be seen that by this arrangement I effect a progressively varying change in the leverage ratio of the lever arm 83' or in other words, vary the leverage distance of the line of contact of the roller 87 with respect to the transfer bar 51 by causing the slide block 86 to progressively vary its position and to move up and down in the slot 85 and thus advance or retract the roller 87 progressively to vary the outer extreme limit of the stroke of the transfer bar 51 and the slide 90 without altering the inner limit or starting position of the transfer bar 51. In other words, the slide 90 and transfer bar 51 will be moved to their maximum outward position as shown in Fig. 2, and the rocker arm 50 will assume the angularly inclined position there shown, with the upper lever arm 83 of the rocker

arm 50 carrying the cam follower 81, also upwardly inclined, to the left of the figure. However, when the transfer bar 51 has been reciprocated to the left of the figure and restored to its original starting position, the rocker shaft and the rollers 81 and 87 will all lie on the same vertical line of centers. Thus, the inner or starting position of the transfer bar will always remain the same at the start and finish of each reciprocation.

In order to impart the progressive rotary or "creeping" motion of the auxiliary cam 105 during the simultaneous rocking motion of this cam and the rocker arm 50, I have provided a system of planetary gearing to turn the cam 105 whereby it will make one rotation on its own axis during the predetermined cycle of oscillations which it undergoes with the rocker arm 50. In the embodiment illustrated, the rocker arm 50 makes about 48 cycles of oscillation to each revolution of the "creep" cam 105. To this end, I mount the oscillatory "creep" cam 105 on the reduced portion 106 of the short shaft 107 and securely clamp the cam in place thereon by means of a nut 108 and a washer 109. The shaft 107 is rotatably mounted in the bearings 110 and 111 respectively integral with the channel member 96 and the housing 44 of the builder unit. Mounted intermediate of the bearings 110 and 111 is a gear 112 which has intermeshing engagement with the drive gear 56 which drives the main cam 48. Provided in the outer side face of the gear 112 is a large circular recess 114 which forms a rim 115 on this side face of the gear, and mounted on the inner wall of this recess is a pinion gear 116 which is freely rotatable on a stud 117 fixedly secured by screw threads to a threaded hole in the side wall of the gear 112 and locked in place by means of a nut 118 on the projecting threaded end of the stud. The pinion 116 has intermeshing engagement with a pair of gears 119 and 120, which gears are of substantially equal width and their combined width substantially equals that of the pinion 116. As shown in Fig. 4, the gear 119 is keyed to the shaft 107 by means of a key 121, and this gear has a hub 122 on which is loosely mounted the other gear 120. The gear 120, however, oscillates with the rocker arm 50; and to attain this result, a pin 125 of stepped formation extends between the rocker arm 50 and the gear 114 and is connected to the rocker arm by the reduced end portion 126 which is received in an opening 128 in the rocker arm 50. The other end portion of the pin 125 is of more reduced size than the end portion 126 and forms a small short cylindrical plug 129 which is inserted within a hole 130 formed in the side face of the gear 120. Thus, the pin 125 serves to bridge the gap between the rocker arm 50 and the gear 120 to couple these parts together for oscillatory motion in unison. The gears 119 and 120, while of equal pitch diameter, differ, however, in their respective number of teeth, the gear 120 having one more or one less tooth than the gear 119. In the planetary gear system thus described, it will be observed that the motion of the gear 119 is dependent upon the revolving motion of the gear 112 and the oscillatory motion of the gear 120. To make this entirely clear, assume for the moment that gear 120 is held stationary. Pinion 116, moving with the continuously rotating gear 112, would simply roll around gear 120. It would at the same time also roll around gear 119, but inasmuch as the latter has a different number of teeth than gear 120, the number of

revolutions of the pinion 116 determined by the number of teeth on gear 120 would effect a partial rotation of gear 119 relative to gear 120. Thus this partial rotation of gear 119 relative to gear 120 may be said to depend upon the revolving motion of gear 112, since we have assumed gear 120 to be stationary. Actually, however, through the pin 125, the gear 120 oscillates with the rocker arm 50 and as it oscillates it affects the rotation of the pinion 116, causing it to turn slower when the angular movement of the rocker arm 50 is in the same rotational direction as that of gear 112, or causing the pinion 116 to turn faster when the angular movements of the rocker arm 50 and the gear 112 are in opposite rotational directions. Since, as before noted, gears 120 and 119 are both in mesh with the pinion 116, any change in the speed of rotation of the latter due to the oscillatory movement of gear 120 will affect a corresponding movement of gear 119. Thus the gear 119 will oscillate back and forth with the rocker arm 50 and will at the same time progressively advance or "creep" around the reduced portion 106 of the shaft 107 and turn relative to the rocker arm 50 because of the different number of teeth present in the gears 119 and 120. Since the gear 119 and the cam 105 are both keyed to the shaft 107 the "creep" cam 105 will therefore participate in exactly the same movement as the gear 119. If desired, it will be obvious that different increments of "creepage" of the oscillatory cam 105 may be obtained as desired by providing various desired tooth differences in the number of teeth on the gears 118 and 120.

In building a bobbin having either of the shapes shown in either Fig. 8 or Fig. 9, the build of the yarn package is accomplished by the use of a variable and cyclic traverse wherein the vertical stroke of the rail 27 is progressively shortened and lengthened in accordance with a predetermined law, governed by the equation of the curve employed for the cam form; and the cycle of shortening and lengthening of the traverse is repeated over and over again, in which the superposed spiraled layers of yarn forming a multiplicity of zones Z, when the bobbin has been built up to the desired diameter. The starting and finishing points of each yarn winding for each cycle or zone always terminate in the same plane, which is that of the bottom or base of the bobbin. This is indicated graphically in Fig. 10, which representation is not intended to be an exact diagram of the winding but is intended to depict only the repeated cycle of shortening and lengthening of the vertical traverse of the ring rail during the winding of each half zone $\frac{1}{2}Z$ indicated in Figs. 8 and 9. The traverse motion of my builder permits "random" doffing of the bobbins since new bobbins may be inserted whenever desired and the winding commenced thereon at any point in the traverse cycle, the yarn wrappings being applied in the same cyclic manner when one cycle has been completed and the point of change for next succeeding cycles is to commence.

This invention insofar as it relates to a mechanical movement "per se" capable of general use in other mechanical combinations than in a textile machine embodying a winding device including traversing means is described and claimed in a copending divisional application Serial No. 404,454, filed July 29, 1941, entitled "Mechanical movement," now Patent No. 2,301,642, November 10, 1942.

I claim:

1. Builder mechanism for reciprocating a rail of a spinning or twisting machine having an oscillatable builder lever operatively connected with said rail, means for oscillating said lever comprising a power driven cam, a slide actuated by said cam, a rocker arm actuated at one end by said slide and having an adjustable element at the opposite end thereof, means for adjusting said element relative to the said arm, means for oscillating a reciprocable bar actuated by said element, and operative connections between said bar and said builder lever for effecting oscillations of said lever and reciprocations of said rail in accordance with the reciprocations of said bar as determined by the adjustment of said element.
2. Builder mechanism for reciprocating a rail of a spinning or twisting machine having an oscillatable builder lever operatively connected with said rail, means for oscillating said lever comprising a power driven gear continuously rotating at uniform speed, a cam rotated by said gear, a slide actuated by said cam, a rocker arm actuated at one end by said slide and having an element at its other end movable along the arm toward and from its axis of rotation, means including a series of gears operatively connected with said power driven gear for moving said element with respect to said rocker arm, a reciprocable bar actuated by said element, and operative connections between said bar and said builder lever for affecting oscillations of said lever and reciprocations of said rail in accordance with the reciprocations of said bar as determined by the adjustment of said element.
3. Builder mechanism for reciprocating a rail of a spinning or twisting machine having an oscillatable builder lever operatively connected with said rail, means for oscillating said lever comprising a power driven gear, a cam rotated by said gear, a slide actuated by said cam, a rocker arm actuated at one end by said slide and having an element at its other end movable along the arm toward and from its axis of rotation, means including a second cam rotatably mounted on the axis of said rocker arm for moving said element relative to the said arm, means for oscillating said second cam in unison with the oscillations of said rocker arm, other means coacting with the last said means and actuated by said driven gear for rotating said cam with respect to said rocker arm to effect movement of said element along said rocker arm, a reciprocable bar actuated by said element, and operative connections between said bar and said builder lever for affecting oscillations of said lever and reciprocations of said rail in accordance with the reciprocations of said bar as determined by the adjustment of said element.
4. Builder mechanism as set forth in claim 3 in which the said second cam is moved through one complete revolution with respect to said rocker arm for a predetermined cycle of oscillations of said rocker arm.
5. Builder mechanism as set forth in claim 3 in which the end of the rocker arm, its axis, and the said element come into vertical alignment during each oscillation of the said arm whereby the end of movement of said rail in one direction remains unaffected by the adjustment of said element.

FRED M. RODDY.

CERTIFICATE OF CORRECTION.

Patent No. 2,364,819.

December 12, 1944.

FRED M. RODDY.

It is hereby certified that error appears in the printed specification of the above numbered patent requiring correction as follows: Page 5, second column, lines 10 and 11, claim 1, strike out the words "relative to the said arm, means for oscil- arm" and insert instead --toward or from the axis of said rocker arm--; and that the said Letters Patent should be read with this correction therein that the same may conform to the record of the case in the Patent Office.

Signed and sealed this 1st day of May, A. D. 1945.
